UNITED STATES PATENT OFFICE.

VINCENT GEHRLEIN, OF ERIE, PENNSYLVANIA, ASSIGNOR TO LOVELL MANUFACTURING COMPANY, OF ERIE, PENNSYLVANIA, A CORPORATION OF PENNSYLVANIA.

WRINGER.

Application filed October 13, 1926. Serial No. 141,281.

Wringers are usually provided with drip boards and these drip boards extend quite a distance out from the front and rear of the wringer. With shipment and storage of wringers it is desirable to have the drip board removed from the wringer and it, therefore, becomes very desirable to have a simple and efficient means for securing the drip board to the wringer frame so that this may be done in the hands of the ultimate user, or at least by the dealer ordinarily handling the wringer. The present invention is designed to permit of a simple yet secure detachable mounting for the drip board. Features and details of the invention will appear from the specification and claims.

The invention is illustrated in the accompanying drawings as follows:—

Fig. 1 shows a perspective view of the wringer.

Fig. 2 a sectional view of a portion of the frame on the line 2—2 in Fig. 1.

Fig. 3 a perspective view of a portion of the bottom bar and drip board mounting.

Fig. 4 a bottom view of a portion of the bottom bar with the drip board removed.

Fig. 5 a similar view with the drip board in place.

Fig. 6 a view of the securing bolt.

1—1 mark the stiles, 2 the bottom or base, 3 the top bar, 4 rolls mounted in the stiles, 5 a drip board, and 6 a reversing plate on the drip board. These may be of common construction so far as described.

Posts 7 are secured to the ends of the drip board and these have feet 8 which are adapted to rest on the bottom bar adjacent to the inner faces of the stiles. The foot 8 has a slot 9 and the bottom bar is provided with a key-hole slot 10, the small part of the slot being adapted to register with the slot 9. A bolt 11 having a head 12 of a size to pass through the large part 45 of the key-hole slot 10 is passed through the enlarged part of the key-hole slot 10 and then moved into the slot 9 and smaller portion of the key-hole slot. The bolt is provided with a squared shank 13 which en-

gages the walls of the slot 9 so as to prevent 50 the bolt turning and the bolt is provided with a wing nut 14 by means of which it may be readily screwed to place. It will be understood that the same construction of foot and wing nut is arranged at each 55 end of the drip board, but one end being shown in detail.

In this way the drip board may be readily assembled without the use of tools and after being assembled is securely mounted and 60 held in place.

What I claim as new is:—

1. In a wringer, the combination of a frame comprising side stiles and a base, said base having slotted openings; rolls in the 65 frame; a drip board with feet on the base and having slots registering with the slots in the base; bolts having heads insertable through the slots in the base and movable into the slots in the feet; and nuts on the 70 bolts adapted to clamp the feet on the base.

2. In a wringer, the combination of a frame comprising side stiles and a base, said base having slotted openings; rolls in the frame; a drip board with feet on the 75 base and having slots registering with the slots in the base; bolts having heads insertable through the slots in the base and movable into the slots in the feet, said bolts having out of round shanks adapted to engage 80 the walls of the slots; and nuts on the bolts adapted to clamp the feet on the base.

3. In a wringer, the combination of a frame comprising side stiles and a base, said base having key-hole openings therein 85 adjacent to the side stiles; a drip board; posts extending downwardly from the drip board adjacent to the stiles, said posts having inwardly extending feet with slots registering with the smaller portions of the 90 key-hole slots; bolts having heads insertable through the larger portions of the key-hole slots and movable into the slots in the feet; and nuts on the bolts.

In testimony whereof I have hereunto set 95 my hand.

VINCENT GEHRLEIN.
